UNITED STATES PATENT OFFICE.

JAMES B. SIMLER, OF CLEVELAND, OHIO, ASSIGNOR TO THE BRUCE MACBETH ENGINE COMPANY, OF CLEVELAND, OHIO, A CORPORATION OF OHIO.

COOLING DEVICE FOR INTERNAL-COMBUSTION ENGINES.

Application filed July 14, 1920. Serial No. 396,177.

To all whom it may concern:

Be it known that I, JAMES B. SIMLER, a citizen of the United States, resident of Cleveland, county of Cuyahoga, and State of Ohio, have invented new and useful Improvements in Cooling Devices for Internal-Combustion Engines, of which the following is a specification, the principle of the invention being herein explained, and the best mode in which I have contemplated applying that principle, so as to distinguish it from other inventions.

My invention relates to internal combustion engines, and particularly to means for controlling the temperature of moving parts, in which it is desirable not to permit overheating. The object of the invention is to provide a simple and efficient device for controlling the temperature of the pistons, whereby overheating of the latter is prevented, and a desired low temperature secured and maintained.

The said invention consists of means hereinafter fully described and particularly set forth in the claims.

As is well known, the pistons of internal combustion engines become heated to a marked degree during the operation of the engine. These pistons are usually hollow and contain, under the present practice, a volume of air which is "dead,"—that is, this air in the interior of these pistons does not circulate, and as a result radiation of heat from the pistons and their consequent cooling, is interfered with. My invention contemplates the provision of means for creating a circulation in the interior of the engine housing, whereby the gaseous content of the interior of the pistons is displaced, and a cooling effect upon the pistons produced.

The annexed drawing and the following description set forth in detail certain means embodying my invention, the disclosed means, however, constituting but one of the various mechanical forms in which the principle of the invention may be applied.

In said annexed drawing:

Figure 1 represents a vertical section of an accepted, well-known type of stationary internal combustion engine, the latter being shown fitted with my invention.

Figure 2 represents, on an enlarged scale, a vertical section of an oil-separator used in connection with my invention.

The illustrated embodiment of my said

invention comprises a duct 1, made of piping of a suitable diameter, the upper end of this duct being connected with the air intake 2. The opposite end of this duct extends into the piston, as shown, and includes a section 3, which is fixed to the interior of the piston and has a sliding connection with the main or stationary portion of the duct 1. The latter is preferably caused to enter the engine housing through the crank case 4, whence it passes upwardly into the cylinder and connects with the movable section 3. The crank case 4 may be an enclosed chamber, in which case it will be provided with a breathing opening 9 through which air may be expelled from and drawn into the casing on reciprocation of the piston, or it may be of open construction.

The air passes through the intake in the direction indicated by the arrow, creates a flow of the gaseous content of the piston out of the latter, through the duct, and into the air intake, as will be readily understood. It will therefore be noted that the resulting displacement of the gaseous content of the piston is effected by exhaustion, and is compensated for by the atmospheric air which enters the crank case directly and through the opening therein, the flow of which is induced by the difference in pressure between the atmosphere and the interior of said piston. This displacement is continuous while the engine is in operation and the required circulation is thus effected.

A valve 5 is preferably introduced in the duct 1 for regulating this flow.

Inasmuch as considerable oil in the form of vapor is contained in the gaseous content of the interior of the crank casing, I provide means in the form of an oil separator 6, for separating such oil therefrom. This separator is placed in the path of flow in the duct, and preferably outside the casing, as shown in the drawing. It consists of any well-known type of separator and its discharge duct 7 is caused to pass back through the crank case and to discharge into the latter, thereby permitting the recovered oil to be re-introduced into the interior of the crank case. The end 8 of this discharge tube is preferably U-shaped to form a trap, as shown.

While but a single cylinder engine is shown to which my invention is applied, it is, of course, obvious that as many of these

devices may be used as there are pistons in the engine, or as may be found necessary.

What I claim is:

1. In an internal combustion engine, the combination of a crank case; a cylinder; a reciprocating piston in said cylinder and having a hollow chamber communicating with said crank case; and means extending into said chamber for establishing communication between the opposite sides of the piston to directly displace the gaseous content of said chamber by exhaustion; the interior of said crank case being directly connected with the atmosphere whereby a flow of atmospheric air is induced and caused to compensate for such displacement.
2. In an internal combustion engine, the combination of a crank case; a cylinder; a reciprocating piston in said cylinder and having a hollow chamber communicating with said crank case; an air intake passage for admitting air to the interior of said cylinder; and a pipe leading from said air intake passage to and extending into the hollow chamber of said piston, whereby the gaseous content of said chamber is displaced by exhaustion; said crank case being directly connected with the atmosphere whereby a flow of atmospheric air is induced and caused to compensate for such displacement.

Signed by me, this 3rd day of July, 1920.

JAMES B. SIMLER.
